ORGANIC PHOSPHITE COMPOUND AND
METHOD OF MANUFACTURING SAMERobert E. Conary and Harry V. Ashburn, Beacon,
N. Y., assignors to The Texas Company, New
York, N. Y., a corporation of DelawareNo Drawing. Application March 25, 1939,
Serial No. 264,119

14 Claims. (Cl. 260—461)

This invention relates to novel organic phosphite compounds, particularly phosphite esters of alkyl ethers of alkylene glycols, and to their method of preparation.

Heretofore, certain aryl and alkyl phosphites have been prepared, such as triphenyl phosphite, tricresyl phosphite, tributyl phosphite, etc. These materials have been suggested as additives for lubricating oil to impart certain advantageous properties thereto, particularly to inhibit bearing corrosion when employed in a motor oil adapted for crank case lubrication.

We have now discovered that a novel group of organic phosphite compounds can be prepared in accordance with the method of this invention, these compounds constituting superior additives for lubricating oil having unexpected and additional properties over those previously known. The compounded oil and the method of lubricating the bearings and cylinders of internal combustion engines with mineral lubricating oil containing these compounds are described and claimed in the co-pending application of Robert E. Conary, Harry V. Ashburn and Paul S. Stuttsman, filed of even date herewith.

The phosphite esters of alkyl ethers of alkylene glycols of this invention are represented by the formula

where X_1 is an alkyl-alkylene oxide group of the type

where R_1 is an alkyl radical having less than nine carbon atoms selected from the group consisting of methyl, ethyl, propyl, butyl, amyl, hexyl, heptyl and octyl, where R_2 and R_3 represent the same or different alkylene radicals (C_nH_{2n}), where n_1 is zero to five, n_2 is one to five, and where X_2 and X_3 represent hydrogen or the same or different alkyl-alkylene oxide groups of the type set forth for X_1 above. By the expression "alkylene radical" as used herein, it is to be understood that this includes the ethylene radical

and the two propylene radicals

and

in which the other two bonds are saturated by

being attached to other atoms or radicals, and does not include the unsaturated olefins. From the above, it is understood that this invention includes the tri-substituted normal phosphite esters, the di-substituted mono-hydrogen phosphite esters and the mono-substituted di-hydrogen phosphite esters, in which each substituent is the group formed by splitting off hydrogen from the hydroxyl radical of an alkyl ether of a glycol selected from the group consisting of ethylene glycol, polyethylene glycols including diethylene glycol, triethylene glycol, etc., propylene glycol and the polypropylene glycols.

The monoalkyl ethers of ethylene glycol have become familiarly known as "Cellosolves"; and the monoalkyl ethers of diethylene glycol have become familiarly known as the "Carbitols." It is thus understood that the phosphite esters of the "Cellosolves" and "Carbitols" are included, as well as those phosphite esters of the alkyl ethers of higher polyglycols formed by condensing two or more ethylene oxide groups with ethylene glycol, or formed by condensing one or more propylene oxide groups with propylene glycol. While the polyethylene glycols and the polypropylene glycols containing more than three condensed groups are known, the corresponding phosphite esters of the alkyl ethers thereof have such high boiling points and are so difficult of separation, that they are considered of lesser practical importance, although they are included within the scope of the present invention. In the case of the phosphite esters of the alkyl ethers of the mono- or polypropylene glycols, it is to be understood that this includes those compounds formed from propylene glycol $HO-CH(CH_3)-CH_2OH$ as well as those from the 1,3 glycol, trimethylene glycol $HO-CH_2-CH_2-CH_2OH$.

As representative of the compounds of this invention, there is mentioned butyl "Carbitol" phosphite which is the trisubstituted normal phosphite ester of the monobutyl ether of diethylene glycol having the formula

and methyl "Cellosolve" phosphite which is the tri-substituted normal phosphite ester of the monomethyl ether of monothylene glycol having the formula

These compounds are prepared by reacting a phosphorus trihalide, such as phosphorus trichloride, phosphorus tribromide, etc., with the corresponding alkyl ether of the glycol or poly-

glycol. The reaction is carried out in the presence of a suitable low-boiling organic solvent and a material which is effective to take up HCl or other hydrogen halide as formed in the reaction. The chlorine of the phosphorus trichloride splits off hydrogen of the free OH group of the alkyl ether of the glycol, forming hydrochloric acid, the valence of the oxygen being satisfied by attaching to the phosphorus atom. This is represented by the equation

where A represents the alkylene oxide or poly-alkylene oxide group of the corresponding glycol or poly glycol and R is the alkyl radical forming the monoalkyl ether thereof. In the presence of free HCl, the resulting normal ester tends to decompose into the acid phosphite ester, and the chloride of the corresponding glycol alkyl ether, as shown by the following equation

But by carrying out the reaction in the presence of a material which reacts readily with HCl to form a stable hydrochloride addition product or a chloride and thereby remove the HCl from the scene of reaction, it can be made to go to substantial completion with the formation of the normal ester. At least three mols of the glycol alkyl ether are used with one mol of phosphorus trichloride in the presence of at least three mols or more of an HCl sequestering reagent to form the corresponding trisubstituted normal phosphite, an excess of the alcohol ether over the theoretical reacting amount apparently being beneficial from the standpoint of completeness of reaction and yield.

In order to produce di-substituted monohydrogen phosphites of these alkyl ethers of alkylene glycols, the same molecular proportions of phosphorus trichloride and the alkyl ether are used so as to replace the three chlorine atoms of the phosphorus trichloride and form the corresponding normal phosphite, but in this case two mols of the HCl sequestering reagent are used so that one mol of HCl is left to react with the normal phosphite to split off one glycol alkyl ether group from the molecule, forming the di-substituted monohydrogen phosphite and the corresponding chloride of the alkyl ether, in accordance with the equation set forth above. These can then be separated by distillation to recover the acid ester.

In order to form the mono-substituted dihydrogen phosphite, the corresponding di-substituted monohydrogen phosphite is reacted with one mol of HCl in the presence of a suitable organic solvent and in the absence of an HCl sequestering reagent, thereby producing the mono-substituted dihydrogen ester and the corresponding chloride of the alkyl ether, according to the equation

These can then be separated by distillation.

The above reactions are carried out generally at low temperatures, such for example as from about 0° F. to about 50° F. In the case of the normal ester and the monohydrogen ester, the phosphorus trichloride is preferably added dropwise to the cooled mixture of alkyl ether, solvent and HCl sequestering reagent. After completion of the addition of the phosphorus trichloride, the mixture is preferably refluxed for a period of time at the boiling point of the solvent used. It is then cooled, may be washed with water to re-

move any free acid, and then dried in the presence of a suitable desiccant, such as anhydrous sodium or calcium sulfate, or filtered without washing in the cases where the compound tends to hydrolyze in the presence of water. The dried or filtered mixture is distilled under vacuum to remove the solvent and any remaining HCl sequestering reagent and unreacted alkyl ether as well as any alkyl ether chloride which may be present. The residue is then distilled under high vacuum to recover the desired ester as a distillate.

Any low boiling aliphatic or aromatic hydrocarbon or chlorinated hydrocarbon solvent can be employed, although preferably one is selected which boils below about 212° F. Examples of suitable solvents are pentane, hexane, heptane, carbon tetrachloride, benzene, and the like. If the reaction is carried out under pressure, liquefied normally gaseous hydrocarbons of the character of propane, butane, and the like may be used; and the temperature of the reacting mass can be controlled by evaporative cooling upon controlled release of pressure to vaporize and liberate a portion of the solvent.

Any suitable HCl sequestering reagent which is non-reactive with the other ingredients of the mix and which can be readily separated from the reaction product, can be employed. Examples of these reagents are pyridine and its homologs, various amines, particularly the tertiary amines such as trimethyl amine, triethyl amine, and the like. Also various alkaline earth carbonates may be employed, such as calcium carbonate.

By way of example, the preparation of the tri-substituted or normal phosphite ester of butyl "Carbitol" is described herein, although it is understood that this is given for the purpose of illustration and the invention is not limited thereto. In this case, one mol of phosphorus trichloride was added dropwise to a cooled, agitated mixture of three mols or more of dry monobutyl ether of diethylene glycol, about 3.3 mols of dry pyridine and an approximately equal weight of dry benzene, while the temperature was maintained between 23-50° F. After complete addition of the phosphorus trichloride, the mixture was allowed to warm up to room temperature, and then heated to boiling and refluxed for two hours. After cooling to room temperature, the mixture was washed with cold water until the wash water gave no acid test to litmus. The mixture was then dried over anhydrous calcium sulfate, and the dried mixture distilled under vacuum to remove remaining benzene, pyridine and butyl ether of di-ethylene glycol. Distillation under vacuum was continued and the desired product passed over at about 455-465° F. under an absolute pressure of 15-20 mm. mercury. This material was an oily colorless liquid soluble in mineral lubricating oil.

The normal phosphite ester of methyl "Cellosolve" was prepared in the same way as set forth above, but in this case the mono-methyl ether of mono-ethylene glycol was substituted for the monobutyl ether of di-ethylene glycol employed in the previous experiment, and after refluxing and cooling, the mix was filtered without washing to remove the precipitated pyridine hydrochloride. The resulting methyl "Cellosolve" phosphite was obtained by vacuum distillation of the filtrate, the desired product passing over at 290-305° F. under an absolute pressure of 10-20 mm. mercury. This material was

also an oily colorless liquid soluble in mineral lubricating oil.

Wherever the expression "phosphorus trichloride" appears in the specification and claims, it is to be understood that other phosphorus trihalides are included under the doctrine of equivalents; likewise, wherever the expression "HCl sequestering reagent" appears in the description and claims, it is to be understood that this includes a reagent which is active to react with other hydrogen halides produced in the reaction by the use of phosphorus trihalides other than the chloride.

Obviously many modifications and variations of the invention as hereinbefore set forth may be made without departing from the spirit and scope thereof, and only such limitations should be imposed as are indicated in the appended claims.

We claim:

1. As a new compound, a phosphite ester of an alkyl ether of an alkylene glycol having the formula

where X_1 is an alkyl-alkylene oxide group of the type

where R_1 is an alkyl radical containing from one to eight carbon atoms, where R_2 and R_3 represent alkylene radicals (C_nH_{2n}) selected from the group consisting of ethylene and propylene, where $n1$ is zero to 5, $n2$ is one to five, and where X_2 and X_3 represent a chemical constituent selected from the class consisting of hydrogen and an alkyl-alkylene oxide group of the type set forth for X_1 above.

2. A new compound in accordance with claim 1, in which the alkylene glycol is an ethylene glycol having not more than three ethylene groups.

3. A new compound in accordance with claim 1, in which the alkylene glycol is a propylene glycol containing not more than three propylene groups.

4. As a new compound, a phosphite ester of a butyl ether of di-ethylene glycol.

5. As a new compound, the normal phosphite ester of the monobutyl ether of di-ethylene glycol.

6. As a new compound, a phosphite ester of the monomethyl ether of ethylene glycol.

7. As a new compound, a normal phosphite ester of the monomethyl ether of ethylene glycol.

8. The method of preparing a phosphite ester

of an alkyl ether of an alkylene glycol of the character of claim 1, which comprises reacting the corresponding alkyl ether of the alkylene glycol with phosphorus trihalide in the presence of an organic solvent and a hydrogen halide sequestering reagent.

9. The method of preparing a normal phosphite ester of an alkyl ether of an alkylene glycol of the character of claim 1, which comprises reacting three mols of the corresponding alkyl ether of the alkylene glycol with one mol of phosphorus trichloride in the presence of at least three mols of HCl sequestering reagent.

10. The method of preparing a di-substituted monohydrogen phosphite ester of an alkyl ether of an alkylene glycol of the character of claim 1, which comprises reacting three mols of the corresponding alkyl ether of the alkylene glycol with one mol of phosphorus trichloride in the presence of two mols of an HCl sequestering agent.

11. The method of preparing a mono-substituted di-hydrogen phosphite ester of an alkyl ether of an alkylene glycol of the character of claim 1, which comprises reacting one mol of the corresponding di-substituted monohydrogen phosphite ester of the alkyl ether of an alkylene glycol with one mol of HCl with the splitting off of one mol of the corresponding alkyl ether chloride.

12. The method of manufacturing the normal phosphite ester of the mono-butyl ether of di-ethylene glycol, which comprises reacting three mols of the mono-butyl ether of di-ethylene glycol with one mol of phosphorus trichloride in the presence of at least three mols of an HCl sequestering reagent.

13. The method of manufacturing the normal phosphite ester of the mono-methyl ether of ethylene glycol, which comprises reacting three mols of the mono-methyl ether of ethylene glycol with one mol of phosphorus trichloride in the presence of at least three mols of an HCl sequestering reagent.

14. The method of manufacturing a normal phosphite ester of an alkyl ether of an alkylene glycol of the character of claim 1, which comprises adding one mol of phosphorus trichloride to a cooled and agitated mixture containing at least three mols of the corresponding alkyl ether of an alkylene glycol, at least three mols of an HCl sequestering reagent and a low boiling organic solvent, refluxing the mixture, and then recovering the resultant phosphite ester by vacuum distillation.
